UNITED STATES PATENT OFFICE.

CLAUS A. EDLUND, OF PROVIDENCE, RHODE ISLAND, ASSIGNOR OF ONE-HALF TO EMIL BERNSTROM, OF PROVIDENCE, RHODE ISLAND; HANNA EDLUND ADMINISTRATRIX OF SAID CLAUS A. EDLUND, DECEASED.

SURFACING-MACHINE.

No. 876,155.

Specification of Letters Patent.

Patented Jan. 7, 1908.

Application filed December 13, 1905. Serial No. 291,522.

To all whom it may concern:

Be it known that I, CLAUS A. EDLUND, a citizen of the United States, residing at the city of Providence, in the county of Providence and State of Rhode Island, have invented certain new and useful Improvements in Surfacing-Machines; of which the following is a specification, reference being had therein to the accompanying drawing.

10 This invention relates to certain new and useful improvements in surfacing machines and pertains more particularly to that class of machines employed in planing, sand-papering, polishing or otherwise dressing the 15 surface of floors, bowling alleys and the like.

This invention has for its object the reduction of a simple machine of a portable character that will cut, grind or polish the surface of a floor or the like.

20 An essential feature of the machine is that it operates automatically and very rapidly and dresses a floor accurately and smoothly leaving the same straight and true and does this work without the aid of a skilled attendant.

25 The old style surfacing machine of this character, whose cutters work in a horizontal plane, have but one cutter head, and when at work its action against the floor served to 30 throw the machine off to one side making it extremely difficult to guide or control the action and direction of the same.

One very essential feature of my device is that the above objectionable features have 35 been overcome by the employment of two cutter heads rotated in opposite directions, or one working against the other, thereby perfectly balancing the pull or action of the cutters or grinders enabling the direction of 40 the machine to be perfectly controlled. These cutting or dressing heads are adjustably mounted on a carriage and may be driven by a motor or in any other desired manner.

One of the features of the invention when 45 sand-paper or polishing rolls are used in the dressing heads, is that two rolls are mounted in each head both rolls being held to rotate around a common center (which is the upright spindle), also to rotate around their 50 own axis. By revolving the rolls in a horizontal plane a true, even and level surface is sure to be obtained, while to rotate the roll

around their own axis brings into action the surface of the material all around the roll. Instead of using sand-paper rolls in the rotating heads, cutters may be used therein for planing the floor if desired, or polishing material may be applied to the rolls to wax or polish a floor in finishing.

The invention is fully set forth in this 60 specification and more particularly pointed out in the appended claims.

In the accompanying drawings: Figure 1 is a plan view of my improved surfacing machine. Fig. 2 is a side elevation of the machine with one of the heads in section. Fig. 3 is a front elevation showing the arrangement of the heads and driving mechanism and floor dressing devices. Fig. 4 is an enlarged sectional view showing the lower portion of 70 the upright shaft and its connection to the horizontal shaft, also a portion of the surfacing rolls and the gears by which said rolls are rotated. Fig. 5 is a reduced side elevation of the machine illustrating the manner of vertically adjusting the surfacing devices. Fig. 6 is an enlarged side elevation of one of the sand-paper rolls. Fig. 7 is an end elevation of said roll. Fig. 8 is a side elevation, partly 80 in section, of the tubular spring tension core for binding the sand-paper in place around the roll. Fig. 9 is an end elevation of said core. Fig. 10 is an enlarged view illustrating the position of the spring tube in serving to bind the covering to the roll.

85 Referring to the drawings 10 is the body of the machine constructed somewhat similar to an ordinary wagon body consisting of a box frame having sides and end pieces, said body being mounted on four wheels 11—11 90 that support said body to roll on ordinary axles 12. Pivoted at 13 to the rear of said body portion is the apron or platform 14 that extends forward out through the front end of the body portion and is held 95 to be adjusted vertically therein, and on the front end of this plate is secured the two operating heads. These heads are similar to each other in construction, the left head (see Fig. 3) includes the upright shaft 16 held to rotate in the corresponding bearing 18, and fixed to the lower end of said upright shaft is the supporting member 20 in which the horizontal roll shaft

21 is mounted, said shaft being held against rotation by a set screw 21^a. Secured to the lower end of said bearing 18 and held against rotation thereon is the beveled gear 22 and 5 rotatably mounted on the shaft 21 on either side of said supporting member 20 are the beveled gears 23—23 each meshing into said fixed gear 22. These gears 23 may each be provided with a long hub 24 on which to 10 mount their respective sand-papering rolls 25—25. By this construction when the upright shaft 16 rotates the horizontal shaft 21 by carrying said two rolls is caused to revolve and as said rolls are revolved around the axis 15 of the upright shaft they are also caused to rotate in a direction against the cut, about their own axis by the engagement of gear 23 on which they are mounted, with the fixed gear 22. The upright bearing 19 is similar 20 in construction to bearing 18 of the opposite head, with the exception that the former is enlarged at 26 forming a box or casing in which the gears 27 are mounted on the upright shaft 17. A similar gear 28 mounted 25 on the horizontal shaft 31 transmits to the carriage its traverse motion through the worm wheel 29 mounted on the axle 12, the worm 30 and flexible connection 32. Power may be applied to run this machine from any 30 convenient source but I have shown an electric motor 40 mounted on the carriage which may receive its current through a flexible cord from a lamp socket battery or any convenient supply, and transmits its motion to 35 said head through the flexible shaft 33 and gears 34, 35, 36, 37, 38 and 39. It will be noted in this connection that the weight of shafts 16, 17 and their respective blocks 20 and rolls 25, is supported solely by the respective pinions 38 which are rigidly secured 40 to said shafts and bear upon the upper ends of bearings 18, 19.

At 41 is the handle by which the machine may be guided by the attendant. 45 At 42 is an upright bolt secured to the bottom of the body portion and extending up through the plate or platform 14, between the plate and body 10, is located a spring 43 of sufficient tension to raise or support the 50 free end of the said platform and its connected heads. Above the platform is another coil spring 44 whose tension may be adjusted by the nut 45 to overbalance the tension of spring 43 and so lower or adjust the height of 55 bearing pressure of the said working rolls with relation to the surface they are acting upon, at the same time provide a resiliency to the heads between the two springs rendering the same in a measure flexible that 60 it may yield or accommodate itself to any undue strain caused by bunches or unevenness in the floor.

My improved manner of attaching the sand-paper or covering to the rolls is as follows: A round hole is formed through the

roll at 42 on a slight angle to its axis, see Fig. 6, in such a manner that a portion of said hole cuts through to the periphery of the roll at 44. Into this hole is inserted a thin tubular member 45 (see Fig. 8) slotted 70 throughout its length at 46, thus providing two spring lips 47 and 48. At 49 is a longitudinal key fixed to said tube for the purpose of engaging a wrench by which said tube may be turned in said hole. In applying the sand-paper or other covering to this roll one end of said covering 50 (see Fig. 10) is turned over the edge of the cut at 44, the opposite end of the covering 51 being carried around the roll and hooked or bent over 80 one of the spring lips 47 in said tubular portion. A wrench is then applied to the said tube and the same is turned in the slot into the position shown in Fig. 10 tightly drawing the said covering around the roll and simultaneously binding both ends in the said slotted portion by the pressure or spring of the tubing.

The construction of my improved surfacing machine is extremely simple, comprising 90 a body 10 mounted on four wheels 11. An apron or platform 14 is pivoted in the rear of said body portion and is adjustably held at its opposite end to work vertically through the front portion of the body frame. On this apron is mounted the cutting or dressing rolls two in each head running in opposite directions. The revolving of these heads in opposite directions is also a most essential feature of my invention as it is found to be 100 impossible to operate such heads in a practical manner except they are balanced by working against each other. Another feature of the invention is that both rolls in each head have a double rotation one around 105 their own axis and the other around a common center. In revolving on their own axis they are preferably caused to turn against the rotation of the contacting surfaces of the rolls thereby increasing the speed of said 110 surface and so increasing the efficiency of the machine.

I have shown and described two sets of dressing rolls, but my invention is not restricted to the use of rolls for this purpose 115 as cutting or polishing heads of any construction may be used, neither is my invention limited to the use of two sets of heads as these heads may be used in pairs, one pair constituting a set and any number of 120 sets may be used without departing from the spirit or scope of my invention. Neither is the invention restricted to the precise construction and arrangement of parts herein shown and described nor to the various details thereof, as the same may be modified or re-arranged in various particulars, one practical embodiment of which has been 125 herein illustrated and described without attempting to show all of the various forms 130

and modifications in which my invention might be embodied.

Having thus described my invention, what I claim as new and desire to secure by Letters 5 Patent, is:

1. A surfacing machine comprising a supporting frame, a vertical shaft mounted to rotate in said frame, a supporting member rigidly secured to said vertical shaft, a horizontal shaft extended through said supporting member, means for preventing rotation of said shaft oppositely disposed dressing rolls mounted on said horizontal shaft, and means for rotating each roll about said horizontal shaft during the rotation of the vertical shaft.

2. A surfacing machine comprising a supporting frame, provided with a bearing sleeve, a vertical shaft mounted to rotate in said sleeve, a pinion secured to said shaft and resting upon the upper end of said sleeve, whereby said shaft is supported, a supporting member rigidly secured to the lower end of said shaft, a horizontally arranged shaft 25 carried by said supporting member, means for preventing rotation of said shaft, dressing rolls, mounted on said shaft, pinions on said rolls, and a second pinion secured to said bearing sleeve and meshing with the pinions 30 of said rolls.

3. A surfacing machine comprising a supporting frame provided with a bearing sleeve, a vertical shaft mounted to rotate in said sleeve, a pinion rigidly secured to said sleeve, a supporting member rigidly secured to the lower end of said vertical shaft, a horizontal shaft extended through said supporting member, means for preventing rotation of said shaft, oppositely disposed dressing rolls 40 mounted on said horizontal shaft, and pinions connected with said rolls and meshing with the pinion on said bearing.

4. In a machine of the character described, a portable carriage, an actuating motor, two 45 upright shafts, means whereby both of said shafts are driven in opposite directions by said motor, a longitudinally disposed shaft connected at the lower end of each of said upright shafts, two floor dressing rolls 50 mounted to rotate on each of said longitudinal shafts, an apron pivoted at one end in said carriage on which the operating mechanism is mounted, and means for adjusting the free end of said apron to regulate 55 the working pressure of the dressing rolls on the surface to be finished.

5. In a machine of the character described, a carriage, an actuating motor located on said carriage, a pair of upright shafts, means 60 whereby both of said shafts are driven in opposite directions, a plurality of floor dressing rolls connected to and revolved around each of said shafts, means for rotating each roll on its own axis as it is carried around 65 said shaft, an apron pivoted at one end in

said carriage on which the operating mechanism is mounted, means for adjusting the free end of said apron to regulate the working pressure of the dressing rolls on the surface to be finished, and means whereby said carriage may be automatically moved to carry said rolls over the surface to be dressed.

6. In a machine of the character described, a portable carriage, an actuating motor, two upright shafts, means for flexibly connecting 70 said motor to drive said shafts, means whereby both of said shafts are driven in opposite directions by said motor, a longitudinally disposed shaft connected at the lower end of each of said upright shafts, two floor dressing 80 rolls mounted to rotate on each of said longitudinal shafts, an apron pivoted at one end in said carriage on which the operating mechanism is mounted, flexible means connected to the free end of said apron for exerting a pressure of said rolls on the surface to be operated upon, means for adjusting said pressure, and means connected to said carriage by which the same may be guided.

7. A machine of the character described, 90 comprising a carriage, an apron pivoted in said carriage, two separate sets of floor dressing devices mounted on said apron, each set of said devices adapted to be rotated in a horizontal plane and in a direction opposite 95 to the other, and means whereby said apron may be raised and lowered to regulate the pressure of said dressing devices on the surface to be dressed.

8. A machine of the character described, 100 comprising a carriage, an apron pivoted at one end in said carriage, two separate sets of floor dressing rolls rotatably mounted on the opposite end of said apron, each set of said rolls adapted to rotate in a direction 105 opposite to the other, a plurality of rolls in each set, means for rotating each roll about its own axis and also about a common center, and means whereby the free end of said apron may be vertically adjusted to regulate the 110 pressure of said dressing rolls on the surface to be dressed.

9. A machine of the character described, 115 comprising a carriage, an apron pivoted at one end in said carriage, two separate sets of floor dressing rolls rotatably mounted on the free end of said apron, means whereby the free end of said apron may be vertically adjusted, each set of said rolls adapted to rotate in a horizontal plane and in a direction 120 opposite to the other, a plurality of rolls in each set, means for rotating each roll about its own axis and also about a common center, and means whereby said carriage may be automatically moved to carry said dressing rolls over the surface to be dressed.

10. In a machine of the character described, 125 comprising two separate sets of floor dressing rolls, each set adapted to rotate in a horizontal plane and in a direction opposite 130

to the other, a plurality of rolls in each set, means for rotating each roll of a set about a common center, and also about its own axis, the engaging surface of each roll to move in 5 a direction opposite to the direction of travel of the same, a carriage on which said dressing rolls are mounted whereby they are moved along over the surface to be dressed,

and means for adjusting the working pressure of said rolls.

In testimony whereof I affix my signature in presence of two witnesses.

CLAUS A. EDLUND.
